[57] **ABSTRACT**

Hair is dyed in a natural-looking color with a composition comprising a carrier compatible with hair in which at least one of the following compounds is dispersed in an effective amount:

2,5'-diamino-bis-(3,2'-pyridyl)amine,
5-hydroxy-5'-amino-bis-(2,2'-pyridyl)amine,
6-amino-pyridylamino (2)-1,4-diaminobenzene, and acid salts, particularly hydrochloric acid salts, thereof.

PYRIDINE DYESTUFF INTERMEDIATES IN A HAIR DYEING COMPOSITION AND METHOD

CROSS-REFERENCES TO RELATED APPLICATIONS

The present application is a continuation-in-part of my copending application Ser. No. 360,449, filed Apr. 16, 1964 now abandoned for "Hair Dyeing Composition and Method."

BACKGROUND OF THE INVENTION

The present invention relates to a method and composition for dyeing keratin-containing material, for instance furs or living human hair and the like, and particularly for dyeing human hair in natural-looking colors.

It has been proposed to use for the dyeing of hair and the like dye intermediates which may be oxidized to a dyestuff while in contact with the hair for a period of about 30 minutes. These dyeing intermediates may be such which may be oxidized per se, i.e. without the presence of a second dye intermediate, or these intermediates may belong to a group which must be oxidized in the presence of another dye intermediate and of an oxidizing agent in order to give the hair dye.

Dye intermediates which alone cannot be oxidized to a hair dye are generally called nuancing dyes or modifiers. Such modifiers include for instance 4-aminodiphenylamine and 4,4'-diaminodiphenylamine. These diphenylamines will serve to give a gray or bluish gray shade to oxidation hair dyestuffs which are formed of p-diaminobenzenes. However, difficulties are encountered due to the poor water solubility of the diphenylamines and, furthermore, only a limited depth of color can be achieved in this manner.

It has also been proposed to use acetates of 4-aminodiphenylamine which has been substituted in the 3-position by an alkoxy group for the dyeing of human hair. However, the free base which is formed upon alkalizing these salts is so poorly soluble in water that only a hardly visible weak coloration is obtained.

It is an object of the present invention to provide a method and composition for the dyeing of human hair which in a simple and economical manner will result in dyeing the hair in a natural-looking color.

SUMMARY OF THE INVENTION

The present invention contemplates dyeing of keratin-containing material and particularly human hair in a natural-looking color by utilizing a composition comprising a carrier adapted for application to the material and having distributed therethrough and dispersed therein at least one compound selected from the group consisting of:

2,5'-diamino-bis-(3,2'-pyridyl)amine,
5-hydroxy-5'-amino-bis-(2,2'-pyridyl)amine,
6-amino-pyridylamino(2)-1,4-diaminobenzene, and acid salts thereof.

DESCRIPTION OF THE PREFERRED EMBODIMENTS

Surprisingly it has been found that hair as well as other keratin-containing materials such as wool, pelts, furs and horny substances can be dyed, and particularly human hair, in a natural-looking color by being treated with a dyeing composition which contains one or more dyestuff intermediates selected from the group consisting of

2,5'-diamino-bis-(3,2'-pyridyl)amine,
5-hydroxy-5'-amino-bis-(2,2'-pyridyl)amine,
6-amino-pyridylamino(2)-1,4-diaminobenzene, and acid salts thereof.

These compounds may be produced by condensation of the aminopyridine derivative with the corresponding chloropyridine or chlorobenzene derivative. The method of producing the compounds is described for instance on pages 105 and 117 of "Das Pyridin und seine Derivate" by H. Maier-Bode and J. Altpeter, published by Wilhelm Knapp at Halle Saale, 1934, and by Takahshi, Saikachi and Tabata, J. Pharm. Soc. Japan, 66, 61 and 62, (1946).

These compounds which are used according to the present invention are much more easily soluble in water than the analogous diphenylamine derivatives, and thus considerably stronger and more intensive hair colors or colorations of other keratin-containing material can be obtained according to the present invention.

Furthermore, surprisingly, it has been found that the compounds which are utilized according to the present invention are reacted by themselves to form a hair dye upon oxidation but that it is also possible to use these compounds as a shading or a nuancing agent in connection with the well-known oxidation dye intermediates of the benzene series and the more recently developed pyridine hair dyes.

Such oxidation dye intermediates which may be used in combination with the bis-(pyridyl)amines and pyridylaminobenzenes of the present invention are described, for instance, on page 504 of "Cosmetic Science and Technology" by E. Sagarin and include the following: p-phenylenediamine, p-toluylenediamine, m-phenylenediamine, m-toluylenediamine, p-aminophenol, p-amino-N-dimethylaniine, 4,4'-diaminodiphenylamine, 4-aminodiphenylamine, 4-amino-4'-oxydiphenylamine, m-diaminoanisole and m-diethylaminophenol.

The more recently developed pyridine dyes are described in three German published applications, DAS 1,142,045, DAS 1,141,748 and DAS 1,149,496 and include the following: 2,6-diaminopyridine, 2,3-diaminopyridine, 4-methoxy-2,6-diaminopyridine, 4-ethoxy-2,6-diaminopyridine, 4-methyl-2,6-diaminopyridine, 4-hydroxy-2,6-diaminopyridine, 3-hydroxy-2,6-diaminopyridine, 3-hydroxy-4-methyl-2,6-diaminopyridine, 3-hydroxy-4-methoxy-2,6-diaminopyridine, 6-methoxy-2,3-diaminopyridine, 6-ethoxy-2,3-diaminopyridine, 2,5-diaminopyridine, 2-dimethylamino-5-aminopyridine, 2-methylamino-5-aminopyridine, 2-diethylamino-5-aminopyridine, 2-ethylamino-5-aminopyridine, 2-amino-5-methylaminopyridine, 2-methylamino-5-methylaminopyridine, 5,5'-diamino-bis-(2-pyridyl)amine and hydrochlorides thereof.

It is an interesting feature of the compounds which are utilized according to the present invention that they may be applied not only in an alkaline medium but also in an acidic medium and that the thus-dyed hair will be light-fast, and the color will be retained even upon repeated washing, and will not rub off, while at the same time the hair treatment is very mild and does not harm the hair. The hair dyes formed according to the present invention may be used within a pH range of from 1.5 to 12.0 and preferably are used within a pH range from 3.0 to 10.0.

It is a further advantage of the hair dyeing compositions and the method of dyeing hair according to the present invention that the oxygen of the air suffices to develop the dye intermediates to dyestuffs. However, it is also possible to utilize oxidizing agents whereby the time required for dyeing the hair or the like will be reduced and the color will become somewhat stronger. Thus, very intensive colors are obtained by using, for instance, hydrogen peroxide as an oxidizing agent while, on the other hand, dyeing without oxidizing agents will avoid any damage to the hair keratin which possibly could be caused by the oxidizing agent.

These compounds which, in accordance with the present invention, are incorporated in a suitable carrier will form between 0.5 and 3 percent by weight of the dyeing composition; however, it is also possible to dye with preparations containing as little as 0.01 percent or as much as 10.0 percent of the above compounds. The oxidation dye intermediates and the pyridine dyes which may be combined with the dye intermediates of the present invention are also preferably applied within the above percentage ranges.

The following examples are given as illustrative only without limiting the invention to the specific details of the examples.

EXAMPLE I

25.0 grams cetyl alcohol
2.0 grams cholesterol

2.0 grams sodium cetyl sulfate are molten and emulsified with 40.0 ml. water of 75° C. To the still-hot emulsion is added a solution of 3.0 grams 2,5'-diamino-bis-(3,2'-pyridyl)amine, in 20.0 ml. water having a temperature of 70° C.

The thus-formed mixture is cooled under stirring to 30° C. and then adjusted with 5 percent aqueous KOH to a pH of 7.0. Thereafter, 4.0 ml. of 25 percent aqueous ammonia solution are stirred into the mixture and the homogeneous mixture is then filled into tubes. The pH of the mixture is 9.8.

EXAMPLE IA

The cream formed according to Example I is evenly brushed onto the hair and left in contact with the hair for 30 minutes. Thereafter, the hair is rinsed and dried. A light dull-brown color is obtained.

EXAMPLE IB

80.0 grams of the cream of Example I are mixed with 20.0 ml. of 6 percent aqueous hydrogen peroxide and thereafter applied to gray hair. After contact with the hair for 30 minutes at body temperature, rinsing and drying, the hair will have an intensive dull brown color.

EXAMPLE II

A cream is produced according to Example I, utilizing, however, as dye intermediates: 2.0 grams p-tolylene-;i amino sulfate, 0.5 grams 5-hydroxy-5'-amino-bis-(2,2'-pyridyl)amine hydrochloride.

By dyeing with the thus-obtained composition as described in Example IB, a natural-looking dark blonde color is obtained. In this case, the bis-(pyridyl)amine acts as modifier.

EXAMPLE III

A cream is produced according to Example I, using, however, as the dye intermediate 3.0 grams 6-amino-pyridyl-amino(2)-1,4-diaminobenzene HCl of the formula:

Dyeing hair with the thus-formed composition in accordance with Example IB will result in a very natural-looking light ash-brown color.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected by Letters Patent is set forth in the appended claims:

1. Composition for dyeing hair, comprising a alkaline aqueous suitable carrier compatible with the hair to be dyed and having distributed therethrough and dispersed therein an effective amount of at least one compound selected from the group consisting of:

2,5'-diamino-bis-(3,2'-pyridyl) amine,
5-hydroxy-5'-amino-bis-(2,2'-pyridyl) amine,
6-amino-pyridylamino(2)-1,4-diaminobenzene, and acid 70

salts thereof.

2. A composition as defined in claim 1, and also including an effective amount of an oxidizing agent suitable for application to hair.

3. A composition as defined in claim 1, and also including an effective amount of an additional oxidation dye intermediate.

4. A composition as defined in claim 3, wherein said additional oxidation dye intermediate is selected from the group consisting of p-phenylenediamine, p-toluylenediamine, m-phenylenediamine, m-toluylenediamine, p-aminophenol, p-amino-N-dimethylaniline, 4,4'-diaminodiphenylamine, 4-aminodiphenylamine, 4-amino-4'-hydroxydiphenylamine, m-diaminoanisole and m-diethylaminophenol.

5. A composition as defined in claim 3, and also containing an effective amount of an oxidizing agent suitable for application to hair.

6. A composition as defined in claim 1, and also including at least one diaminopyridine selected from the group consisting of 2,6-diaminopyridine, 2,3-diaminopyridine, 4-methoxy-2,6-diaminopyridine, 4-ethoxy-2,6-diaminopyridine, 4-methyl-2,6-diaminopyridine, 4-hydroxy-2,6-diaminopyridine, 3-hydroxy-4-methyl-2,6-diaminopyridine, 3-hydroxy-4-methoxy-2,6-diaminopyridine,

25 6-hydroxy-4-methyl-2,3-diaminopyridine, 6-methoxy-2,3-diaminopyridine, 6-ethoxy-2,3-diaminopyridine, 2,5-diaminopyridine, 2-dimethylamino-5-aminopyridine, 2-methylamino-5-aminopyridine, 2-diethylamino-5-aminopyridine, 2-ethylamino-5-aminopyridine, 2-amino-5-dimethylaminopyridine, 2-amino-5-methylaminopyridine, 2-methylamino-5-methylaminopyridine and hydrochlorides thereof.

7. A composition as defined in claim 6, and also containing an effective amount of an oxidizing agent suitable for application to hair.

8. A composition as defined in claim 7, wherein said oxidizing agent is hydrogen peroxide.

9. A composition as defined in claim 1, wherein said compound is present in said carrier in an amount equal to between about 0.01 and 10 percent of the weight of said composition.

10. A composition as defined in claim 1, wherein said compound is present in said carrier in an amount equal to between about 0.5 and 3 percent of the weight of said composition.

11. A composition as defined in claim 9, wherein said compound is selected from the group consisting of 2,5'-diamino-bis-(3,2'-pyridyl) amine and the hydrochloride thereof.

12. A composition as defined in claim 9, wherein said compound is selected from the group consisting of 5-hydroxy-5'-amino-bis-(2,2'-pyridyl) amine and the hydrochloride thereof.

13. A composition as defined in claim 9, wherein said compound is selected from the group consisting of 6-amino-pyridylamino(2)-1,4-diaminobenzene and the hydrochloride thereof.

14. The method of dyeing hair which comprises applying to the hair an effective amount of the composition of claim 1.

15. The method of dyeing hair which comprises applying to the hair an effective amount of the composition of claim 2.

16. The method of dyeing hair which comprises applying to the hair an effective amount of the composition of claim 3.

17. The method of dyeing hair which comprises applying to the hair an effective amount of the composition of claim 4.

18. The method of dyeing hair which comprises applying to the hair an effective amount of the composition of claim 5.

19. The method of dyeing hair which comprises applying to the hair an effective amount of the composition of claim 6.

20. The method of dyeing hair which comprises applying to the hair an effective amount of the composition of claim 7.

21. The method of dyeing hair which comprises applying to the hair an effective amount of the composition of claim 9.
